UNITED STATES PATENT OFFICE.

LOUIS S. GRUBER, OF ARNOLD, PENNSYLVANIA, ASSIGNOR TO LUISE GRUBER, OF PITTSBURGH, PENNSYLVANIA.

WINDOW.

Application filed June 22, 1921, Serial No. 479,494. Renewed July 16, 1923.

To all whom it may concern:

Be it known that I, LOUIS S. GRUBER, a citizen of the United States, and a resident of Arnold, in the county of Westmoreland 5 and State of Pennsylvania, have invented a new and useful Improvement in Windows, of which the following is a specification.

The objects of the invention are to provide a window construction which will be 10 durable, compact, convenient to clean and easy to operate; which can be easily repaired whenever necessary; and which can be swung to a position to permit the full space occupied by the window to be utilized.

15 Further objects are to provide convenient means for balancing the sashes and for locking them into any desired position; to provide screens forming a part of the window construction proper which can be easily 20 attached to or released from the sashes and which will be completely hidden when not in use; to prevent the leakage of rain or melted snow, which trickles down the exterior of the window, into the interior of 25 the lower sill; and to produce a window in which all of the operating mechanism therefor is protected and is out of sight so as to present a pleasing appearance.

The window illustrated as the preferred 30 embodiment of the invention is constructed entirely of metal, the outer casing, the main frame and sash frames being formed of suitably shaped pieces of sheet metal attached together by any well known means. 35 These parts which are exposed are preferably made of some metal which is capable of resisting the elements as for example, sheet copper. The particular material used, however, forms no part of the invention as 40 any suitable material may be used and it is not intended to limit the invention beyond that particularly pointed out in subsequent claims.

In the accompanying drawings forming a 45 part of this specification, the same reference characters denote corresponding elements through the several views in which Fig. 1 is an elevation showing the window completely assembled, the screens and operating mechanism being indicated in dotted lines; Fig. 2 a vertical sectional view on line II-II, Fig. 1; Fig. 3 a transverse vertical sectional view with parts shown in elevation on line III-III of Fig. 1; Figs. 50 4 and 5 fragmentary sectional views with

parts in elevation showing details; Fig. 6 a transverse horizontal sectional view on line VI-VI of Fig. 1; Fig. 7 an enlarged detail sectional view of the actuating mechanism for the sashes taken on line VII-VII 60 of Fig. 1; Fig. 8 a fragmentary view similar to Fig. 7 showing a modified form of the actuating mechanism; Fig. 9 a section also showing the operating mechanism taken on line IX-JX of Fig. 7; and Fig. 10 is a 65 fragmentary detail view showing the relative positioning of the parts of the locking device illustrated in Fig. 4 when operatively engaged.

The window comprises the outer casing 70 1 so shaped as to provide a recess 2 in which is hingedly supported at 3 and 3' the main frame 4, in which the vertically slidable sashes 5 and 6 of a well known type are mounted. The outer casing 1 is formed at 75 its top with a depending portion 7 and at its sides with inwardly projecting portions 8 which act to form a limiting abutment or stop for the frame 4 when said frame occupies its normal position as illustrated in 80 Fig. 1, and in full lines in Fig. 6. The frame 4, however, may be swung outwardly to the position indicated by the dotted lines in Fig. 6 so as to render it possible to utilize the entire opening through the casing 1. 85 This is found to be of particular importance in office buildings and similar structures for the admission of large safes or pieces of furniture. The window is also swung to its dotted line position for the purpose of cleaning the exterior thereof.

At one side of frame 4 are mounted the spirally grooved shafts 9 and 10 journaled at their upper ends in a bearing bracket 11 and at their lower ends in a pair of spaced 95 bearing blocks 12 and 13, respectively. The shafts have attached near their lower ends pinions 14, 14' meshing with the respective pinions 15, 15', both of the latter encircling a rod 16 slidable in an aperture 17 in block 100 12 and a recess 18 in block 13. Intermediate its ends, the rod 16 carries a pin 19 which is adapted to fit into the grooves 20, 21 in the adjacent faces of the respective pinions 15, 15' for a purpose to be presently explained.

In Fig. 7, the pinions 15 and 15' are shown as positioned adjacent each other leaving but a small space between their abutting faces, while in Fig. 8 is illustrated 110

a modified form in which the pinions are spaced apart by the abutting arcuate bosses 20', the width of the open space indicated at 19' being slightly greater than the width 5 of the pin 19. The length of the pin 19 in this form is less than the distance between diametrically opposed portions of the bosses 20' so as to freely rotate within the space 19' without touching the same. The construction 10 in Fig. 8 permits the shifting of the rod and pin 19 to engage either pinion without first bringing the grooves in the faces of the same into alignment, the pin 19 being simply projected into the space 19' 15 and turned therein until it comes into a position to align with the groove into which it is to be forced.

The bearing block 12 is equipped with a pin 22 provided with a rounded end spring-pressed into either of two series of shallow 20 impressions 23 formed on the rod 16 and a similar pin 24 fits into the depressions 25 in the face of pinion 15, the block 13 also being similarly equipped as shown at 26 for the 25 purpose of slightly retarding free rotation of the pinions. The end of rod 16 has a handle 27 attached thereto to which access may be had through the closure 28 in the frame 4. The open position of closure 28 30 is indicated by dotted lines in Figs. 3 and 7.

Sliding upon the shafts 9 and 10 are the respective nuts 29, 30, each nut being provided with an internal tongue or similar device for engaging the spiral groove of the 35 shaft. The nut 29 is connected to the lower sash and the nut 30 to the upper sash by an extension 30' or 31 which is preferably attached adjacent the upper end of the sash. These extensions project through slots 40 provided in the sash guiding grooves.

Rotatably mounted in the upper and lower ends of the frame 4 are spring rollers 33 and 34. Upon each roller is wound a flexible screen 35 such as is commonly used 45 for excluding insects from doors and windows, whose width is slightly greater than the width of the window sash so that the edges thereof project within slots provided in the sash grooves, the right hand edge as 50 viewed in Fig. 1 riding in the same slot through which the extension attached to nut 30 or 31 projects as previously described. The rollers normally wind and retract the screens into the position illustrated in Fig. 55 1, the roller 33 cooperating with the upper sash and the roller 34 with the lower sash in a manner to be presently described.

Each of the rollers is removably mounted and since the construction used for this purpose is substantially the same for both rollers only that used in connection with one need be described in detail. A pintle 36 on one end of the roller rides in an aperture in the bracket 37 while the squared extension 60 38 at its other end is retained in the

slot 39 in bracket 11 by a latch 40 pivoted at 41 and locked as shown at 42. The means for retaining the squared extension on the lower roller differs from that of the upper one merely in extending the slot or recess in 70 the bracket upwardly and providing an angular offset adjacent its upper extremity, and in pivoting the latch so that the normal position of its axis is vertical instead of horizontal, as clearly shown in Fig. 3. 75

The screens are prevented from being completely wound upon the spring rollers by catches 43 fastened to the free end of each screen which projects through a slot in the sill or lintel for that purpose, the catches 80 being of such dimensions as to prevent their passing through the said slot. The catch acts as a limiting means for the screen and is held firmly in position by the tension of the roller for engagement with the end of 85 the spring-pressed sliding bolt 44 located in the sash of the window.

For the purpose of locking the sashes in various positions as may be desired, several 90 means are employed. In the form illustrated in Fig. 3, shafts 9 and 10 are provided with a series of recesses 45 with which the catches 46 carried by the nuts 29 and 30 coact. The main body of the catch 46 is formed of spring metal and its bent end extends through an opening in the sliding nut so as to enter one of the several recesses 45 to lock the same at any desired height. In the normal operation of the device, the end 100 of the catch is withdrawn and the catch moved about its point of attachment 47 as a pivot out of register with the opening through the nut.

In Fig. 4, the nut 29 is held at any desired position by the sliding lock 48, the lock being pivotally and slidably mounted upon a rod 49 located at the side of the shaft 9. The main body of the lock 48 is provided with a pair of spaced fingers 50 adapted to straddle the nut 29 and to be swung into the 110 position indicated in Fig. 4, the lock being pivotally swung disengaging the nut when not desired. By sliding the lock up or down upon the rod 49, the same may be positioned to lock the nut and attached sash in any 115 desired position. Due to the loose fit of the lock upon the rod any pressure upon either finger 50 tends to force the lock askew resulting in a binding action effectively holding the same against vertical movement. 120

In some instances, it has been found highly desirable to equip the window with means for preventing the entrance of unauthorized persons such as burglars. Such means as shown in Fig. 5, 51 being a series 125 of spaced metal rods or bars projecting upwardly through the lower sill which are attached to the lower end of the sash 6 thus forming a barrier when the sash is raised.

In order to prevent the rain or melted snow 130

which trickles down the exterior of the panes from entering the hollow sill construction and causing damage, and also to prevent the same collecting upon the sill, 5 the sill 52 is inclined as clearly shown in Fig. 2 so that any liquid collecting thereon will be readily discharged, the grooves 53 being provided to facilitate such action.

For holding the window frame 4 in its 10 operative position in the outer casing a combination latch and lock 54 is provided as shown in Fig. 1, the portion 55 coacting with the portion 56 mounted upon the casing 1 in the usual manner. If it is desired 15 to prevent opening of the frame 4, the catch 54 may be locked by inserting a key through the key slot 57.

The operation of the device is as follows: With the form of actuating mechanism 20 shown in Fig. 7, in order to shift the pin 19 from the grooves in either pinion 15, 15', it is first necessary to bring the oppositely facing grooves 20 and 21 into alignment, in which position of the parts, the pin 19 may 25 be selectively engaged with either pinion by longitudinally moving the rod 16. Subsequent rotation of the rod will rotate the pinion. The turning of pinion 15 or 15' results in the rotation of the corresponding shaft 30 9 or 10 and the sliding nut and its sash will be moved due to the cooperation between the nut and spiral groove in the shaft. Turning in one direction will cause the sash to ascend while turning in the opposite direction will 35 obviously cause it to descend. By positioning the pin 19 so as to partially project into both grooves 20 and 21 both sashes may be moved simultaneously if desired, or a single sash may be moved at a time by projecting 40 the pin 19 entirely within the groove of a single pinion, the disengaged pinion being prevented from turning, and allowing the sash to lower under the influence of gravity, by the spring pressed pins 24 or 26 as the 45 case may be, the tension of the latter means not being sufficient, however, to prevent the sash being moved by force, if desired.

With the form shown in Fig. 8, the pin 19 may be projected into the grooves in either 50 pinion, as desired, as previously described, and although this form is not capable of causing simultaneous actuation of the sashes, it makes possible the shifting of said pin from engagement with one pinion into 55 engagement with the other regardless of the relative position of the other and without first bringing the opposite grooves of the two pinions 15 and 15' into alignment.

When the sashes have been moved to the 60 positions desired, they may be securely locked at such points by releasing the catch 54, swinging the frame 4 inwardly on its hinges to the dotted line position in Fig. 6 and setting the locking means 46—47 Fig. 3, 65 or 48—50 Fig. 4, as previously explained,

when the frame is again swung into and locked in the position shown in full lines in Fig. 6 or in Fig. 1.

At night, it is intended to position and lock the sashes so that the open spaces between their ends and the frame are not of sufficient size to permit the entrance of a person, thus giving the benefit of a partially open window without the fear of unauthorized persons entering therethrough. For a 75 similar purpose, the construction shown in Fig. 5 may be used.

The screens for preventing the entrance of insects are normally retracted by releasing the bolt 44 from the catch 43. When 80 the sash is moved to its full closed position, and the bolt 44 is spring-pressed to the left, Fig. 1, so as to bring its end into position to be contacted by the curved portion 43' of the catch, the bolt will engage the slot of the 85 catch thus locking the screen to the window sash. Either a raising or lowering of the sash when the screen is thus attached will cause the screen to be moved therewith thus closing the space between the sash and 90 frame. The screen may be released regardless of the position of the sash by simply drawing the bolt 44 to the right so as to disengage the catch 43 when the tension of the 95 spring roller will retract the screen to the position indicated in Fig. 1.

I claim:

1. A window comprising a frame, sashes mounted in said frame, operating means for said sashes comprising a pair of spirally 100 grooved shafts journaled in said frame, the lower ends of said shafts resting upon a pair of bearing blocks, a sliding nut mounted upon each of said shafts and capable of longitudinal movement thereon, 105 said nuts being connected to the upper and lower sashes, respectively, pinions on the lower ends of said shafts, pinions having inner confronting grooved faces meshing respectively with said first-mentioned pinions and positioned between said bearing blocks, means for selectively actuating either of the last mentioned pinions comprising a longitudinally movable rod mounted in said bearing blocks and passing through the last 115 mentioned pinions, and a pin passing through the rod for cooperating with the grooves in the faces of said pinions.

2. A window comprising a frame, sashes mounted in said frame, operating means for each of said sashes comprising a spirally 120 grooved shaft mounted in said frame, a sliding nut on said shaft capable of longitudinal movement thereon, said nut being connected to its sash, means for locking said nut to the shaft to prevent relative movement therebetween, and means enclosed in said frame for actuating the said operating means.

3. A window comprising a frame, sashes 130

mounted in said frame, operating means for said sashes comprising a pair of spirally grooved shafts journaled in said frame, a sliding nut mounted upon each of said shafts capable of longitudinal movement thereon said nuts being connected to the upper and lower sashes, respectively, pinions on the corresponding ends of said shafts, pinions meshing respectively with said first men-

tioned pinions, means for selectively actuating either of the last mentioned pinions, and means for retarding free movement of the same.

In testimony whereof I sign my name.

LOUIS S. GRUBER.

Witness:

EDWIN O. JOHNS.
